UNITED STATES PATENT OFFICE

YVON BRANCART, OF BONQUIERES, BELGIUM

SOLE PLATE FOR GLASS ANNEALING AND LIKE FURNACES

Application filed February 14, 1930; Serial No. 428,394, and in Belgium February 14, 1929.

The present invention relates to glass annealing and similar furnaces, which are used for slowly cooling glass plates and sheets after casting. Such furnaces comprise near 5 their inlet opening, a slab or sole made of refractory blocks, on which the glass plate coming from the casting table is slidden in order that it may rest and set before it is placed on the conveyor which carries it 10 through the successive cooling zones of the furnace. At the time the glass plate is brought into the furnace, the refractory sole is subjected to sudden heating, which results in an expansion of the blocks composing it 15 followed by a contraction of same when the glass plate cools and is pushed on the conveyor. As a result of these successive expansions and contractions the sole blocks get disjointed, and it may occur that the widened 20 joints mark themselves in relief on the lower side of the glass plates, which are still plastic when brought into the annealing furnace.

The invention has for its object to remove this inconvenience by preventing the sole 25 blocks from getting disjointed without counteracting their free expansion and contraction. It has also the object to avoid the bulging of the glass plates or sheets which tends to take place during their cooling on the sole. 30 The first object is attained by subjecting the sole blocks to an elastic compression acting from outside towards the inside of the sole, so as to keep the blocks permanently applied against each other, as well when expanding as when contracting. To this end I 35 arrange within the sole plate metal rods extending crosswise, the projecting ends of which are provided with springs which press the blocks towards the inside of the sole. These rods may pass through the blocks or 40 between them, along the joints.

On the other hand, to oppose the tendency of glass plates to bulge on cooling, the sole is 45 given a slightly concave shape, so that the plate, which is still plastic, takes that shape when it is first slidden on the sole, and, afterwards as it tends to bulge, it becomes substantially plane.

50 In the accompanying drawing, which

shows by way of example constructional forms of the invention:

Fig. 1 is a perspective view of the sole.

Fig. 2 is a plan view of the same.

Fig. 3 is a sectional view on a greater scale, 55 of a part of the same.

Fig. 4 shows in perspective a block of special shape.

Fig. 5 is a front elevation of the sole showing the concavity of same. 60

The joints of the blocks 1 forming the sole of the annealing or other like furnace are provided with channels 2 through which pass the metal rods 3, and with channels 4 at right angles to the first ones and vertically 65 offset relatively thereto, through which pass other metal rods 5 crossing the rods 3 at right angles. The ends of all these rods project slightly beyond the sides of the sole and support metal bars 6 which are pressed 70 against the blocks 1 by spiral springs 7 coiled around the rods and maintained by nuts 8 screwed on said rods.

When the blocks 1 expand, they push the bars 6 along the rods 3, 5 and compress the 75 springs 7, which afterwards, when the blocks contract, expand again, pushing them back inwardly and maintaining them closely applied against each other at all times.

Instead of being placed in the joints between the blocks 1, the rods 3 and 5 may pass through the blocks in channels bored therethrough, as shown at 2 and 4 in Fig. 4. The block 11 illustrated in that figure has a tongue 12 and a groove 13 adapted to engage with 80 grooves and tongues on other similar blocks, in order to increase the stiffness of the sole. However, blocks of any shape and type may be employed.

The upper surface of the sole may be partly 85 curved inwardly in the transverse direction, to counteract the bulging of the glass plates. This arrangement is shown in Fig. 5, in which 90 14 indicates the concave part of the surface situated at the entrance of the furnace, and 15 95 the flat part which follows said concave part and on which the glass plate is made to slide when it is cooled sufficiently to have no more tendency to bulge.

Obviously, the constructional details above 100

described and illustrated on the drawing have no limitative character and they may be modified without departing from the present invention.

5 I claim:

1. A sole plate for glass annealing and like furnaces, said sole plate comprising a plurality of blocks arranged side by side, metal rods extending through said plate both longitudinally and transversely thereof, and means on the ends of said rods for exerting a resilient inward pressure on said blocks.
- 10 2. A sole plate for glass annealing and like furnaces, said sole plate comprising a plurality of refractory blocks arranged side by side, metal rods extending between adjacent blocks both longitudinally and transversely of said plate, the ends of said rods projecting outwardly beyond the sides of said plate, and 20 spring means on said projecting ends for exerting an inward pressure on said blocks.
- 15 3. A sole plate for glass annealing and like furnaces, said sole plate comprising a plurality of refractory blocks arranged side by side, said blocks having grooves in their side faces, said grooves forming continuous passages both longitudinally and transversely of said plate, metal rods extending through said longitudinal and transverse passages, the 25 ends of said rods being screw-threaded and projecting beyond the sides of said plate, nuts on the screwthreaded ends of said rods, bars bearing on the sides of said plate, and springs interposed between said nuts and said bars.
- 30 4. A sole plate for glass annealing and like furnaces, said sole plate comprising a plurality of refractory blocks arranged side by side, a portion of said sole plate being transversely concave, metal rods extending 35 through passages between said blocks both longitudinally and transversely of said sole, and spring means on the ends of said rods for holding said blocks in mutual contact.
